UNITED STATES PATENT OFFICE.

ISAIAH NEWELL, OF HAVERHILL, MASSACHUSETTS.

DESIGN FOR A WATER RECEPTACLE OR BOTTLE.

No. 37,907.

Specification for Design.

Patented March 20, 1906.

Application filed February 8, 1906. Serial No. 300,188. Term of patent 14 years.

To all whom it may concern:

Be it known that I, ISAIAH NEWELL, a citizen of the United States, and a resident of Haverhill, in the county of Essex and State of Massachusetts, have invented a new, original, and ornamental Design for Water Receptacles or Bottles, of which the following is a specification, reference being had to the accompanying drawing, forming a part thereof.

The accompanying drawing is a perspec-

tive view of my design for water receptacles or bottles.

I claim—

The ornamental design for a water receptacle or bottle, as shown.

ISAIAH NEWELL.
